DESIGN FOR A SWAGING TOOL

Llewellyn P. Jones, Philadelphia, Pa.

Application March 19, 1941, Serial No. 99,715

Term of patent 7 years

To all whom it may concern:

Be it known that I, Llewellyn P. Jones, a citizen of the United States, residing at Philadelphia, in the county of Philadelphia and State of Pennsylvania, have invented a new, original, and ornamental Design for a Swaging Tool, of which the following is a specification, reference being had to the accompanying drawing, forming part thereof.

Figure 1 is a side elevational view of a swaging tool showing my new design.

Figure 2 is an elevational view of one end of the tool, and

Figure 3 is an elevational view of the opposite end of the tool.

I claim:

The ornamental design for a swaging tool, as shown.

LLEWELLYN P. JONES.
